Thomas Parkinson.
BY
Arthur C. Brown
ATTORNEY

UNITED STATES PATENT OFFICE.

THOMAS PARKINSON, OF TOPEKA, KANSAS.

FURNITURE CASTER.

Application filed September 25, 1922. Serial No. 590,328.

To all whom it may concern:

Be it known that I, THOMAS PARKINSON, a citizen of the United States, residing at Topeka, in the county of Shawnee and State 5 of Kansas, have invented certain new and useful Improvements in Furniture Casters; and I do declare the following to be a full, clear, and exact description of the invention, such as will enable others skilled in the art 10 to which it appertains to make and use the same, reference being had to the accompanying drawings, and to the figures of reference marked thereon, which form a part of this specification.

15 This invention relates to furniture casters, and particularly to a novel means for securing the caster pintle in a socket in the leg of the article of furniture to which it is to be applied.

20 The novel construction of the caster-fastening means which constitutes my invention will be clearly understood by reference to the following description in connection with the accompanying drawings, 25 in which:

Fig. 1 is a perspective disassociated view of one end of a furniture leg, the fastening jaws, the expander for the jaws and the caster.

30 Fig. 2 is a longitudinal sectional view through a portion of the leg, through the jaws and through the expander, the caster being shown in elevation with the parts being in position to expand the jaws against 35 the interior wall of the leg.

Fig. 3 is a view similar to Fig. 2 showing the jaws in expanded position.

Fig. 4 is a cross sectional view on the line 4—4 of Fig. 2.

40 Fig. 5 is a cross sectional view through a slightly modified form of expander block with the position modified to conform thereto.

Fig. 6 is a cross section through a further 45 modification showing the jaws as channel-shaped with a rectangular expander between them, and

50 Fig. 7 is a sectional view through a wooden leg showing the jaws and caster associated therewith.

Referring now to the drawings by numerals of reference: 1 designates a hollow leg which may be applied to any article of furniture. The leg shown in Fig. 1 is preferably metal and it is adapted to receive a 55 caster 2 having a threaded pintle 3 at the

base of which is a collar 4 provided with an opening 5 to receive a pin or spanner wrench by means of which the collar and pintle may be turned in unison. 60

The pintle is fastened into the leg by a friction device consisting of two jaws, 6 and 7, which are hinged together by a hinge 8. The two jaws are substantially semi-circular in cross section, and they constitute a barrel-shaped guide for the expander block 9. The concave portions 10 and 11 of the jaws 6 and 7 are tapered; that is, they are smaller at the lower ends than at the upper ends to receive a cone-shaped block 9. Therefore, 70

when the block moves down toward the lower ends 12 and 13 of the jaws 6 and 7, the jaws will be expanded, and when it is received in the upper portions of the concavities 10 and 11, the jaws may be retracted 75

or thrown together. In order to guide the block and prevent its rotative movement with respect to the jaws, and pins 3, I have arranged diametrically oppositely located ribs or wings 14 and 15 which are received 80 between the edges of the jaws 6 and 7. The lower ends of the jaws 6 and 7 are provided with outstanding lugs or projections 16 and 17, which may abut against the lower edge 18 of the leg 1 so that the jaws will 85

not recede too far within the hollow leg. The jaws are also provided with grooves 19 and 20 which are for the purpose of making the walls of the jaws thin so that portions of the jaws on the opposite sides of the 90 grooves can flex. The purpose of flexing the jaws slightly is to maintain an intimate contact between the jaws and the block 9. When the block 9 is in the deeper parts of the concavities 10 and 11, the edges of the 95 jaws are right against the wings 14 and 15. When the block moves down toward the ends 12 and 13, however, there would be a tendency for the edges of the jaws to move away from the wings 14 and 15, but by providing the grooves 19 and 20 so that the portions of the jaws on the opposite sides of the grooves can flex slightly the intimacy 100

between the wings and the edges of the jaws can be maintained. In other words, when the block is near the lower ends of the jaws, the jaws will move away to an expanded position and instead of the space between them being circular, it would have a tendency to be oval, were it not due to the fact 105 that the grooved portions make the jaws turn at those points and allow the edges 110

- to spread so that the space will be circular irrespective of the position of the block. Therefore the entire outer surfaces of the jaws will abut against the inner wall of the leg when they are expanded. By reference to Fig. 2, it will be observed that the block is relatively high or in the deeper portions of the concavities 10 and 11 that the pintle is screwed in the block and the spanner or other wrench, or a nail for example, may be caused to engage the opening 5 so that the collar 4 will be turned. The threaded connection between the pintle 3 and the block 9 will cause the block to move down toward the end of the leg, expanding the jaws to a position shown in Fig. 3 so that the pintle will be tightly located within the leg. If it is desired to remove the caster, a reverse movement of the collar will cause the expander block to move up in the deep portions 10 and 11 of the jaws 6 and 7, so that the jaws can be contracted as shown in Fig. 2 and then the jaws and pintle can be removed from the leg.
25. In Fig. 5 I have shown a slightly modified form in which the jaws 21 and 22 have semi-rectangular concavities 23 and 24. They receive a square block 9' corresponding to the expanding block 9.
30. In Fig. 6, the jaws 25 and 26 are channel-shaped, together enclosing a substantially rectangular space. A square block 9 similar to the one shown in Fig. 5 is also received by the jaws 25 and 26.
35. In Fig. 7 a wooden leg 27 is shown, having a recess 28 to receive the jaws in a manner similar to the manner above described. The jaws for the wooden legs preferably are provided with spurs 29 and 30 to bite into the wood to more securely fasten them thereto. Similar spurs may be shown on jaws for metallic legs but ordinarily these are not necessary. It will be apparent from the foregoing that a pintle can be conveniently attached to and removed from a furniture leg with dispatch and convenience, and that when the caster is fastened in place, it will be tightly held until the jaws are released. The expander block 9 can exert considerable
40. pressure in the opposite direction so as to force the jaws firmly against the inner wall

of the inner leg or socket as the case may be to effect a firm mechanical contact which will prevent accidental disassociation of the pintle from the furniture to which it has been attached.

What I claim and desire to secure by Letters Patent is:

1. In combination a caster having a threaded pintle, outwardly movable jaw members, hinged at their upper ends between which the pintle is received, the jaw members when in co-operative position forming an inverted conical recess and a jaw expander in threaded engagement with and movable longitudinally of the jaws to expand them when in one position and to permit them to contract when in another position.

2. In combination a caster having a threaded pintle, two concave outwardly movable jaw members hinged at their upper ends between which the pintle is received, the concavity of the jaw members having guide grooves, a jaw expander in threaded engagement with the pintle and wings on the expander engaging the longitudinal grooves, the inner walls of the jaw members being inclined upwardly and outwardly so that when the expander is moved toward the base of the pintle the jaws will expand and when the expander is moved away from the base of the pintle the jaws may contract.

3. In combination a caster having a threaded pintle, two concave outwardly movable jaw members hinged at their upper ends between which the pintle is received, the concavity of the jaw members having guide grooves, a jaw expander in threaded engagement with the pintle and wings on the expander engaging the longitudinal grooves, the inner walls of the jaw members being inclined upwardly and outwardly so that when the expander is moved toward the base of the pintle the jaws will expand and when the expander is moved away from the base of the pintle the jaws may contract, and wood engaging tines on the exteriors of the jaws.

In testimony whereof I affix my signature.

THOMAS PARKINSON.
